UNITED STATES PATENT OFFICE.

GEORGE WASHINGTON GOOLSBY, OF DECHERD, TENNESSEE.

DESIGN FOR A MUSICAL INSTRUMENT.

Application filed February 13, 1924. Serial No. 8,625. Term of patent 14 years.

To all whom it may concern:

Be it known that I, GEORGE W. GOOLSBY, a citizen of the United States, residing at Decherd, in the county of Franklin and State of Tennessee, have invented a new, original, and ornamental Design for a Musical Instrument, of which the following is a specification, forming part thereof.

The figure is a perspective view of a musical instrument showing my new design.

I claim:

The ornamental design for a musical instrument, as shown.

GEORGE WASHINGTON GOOLSBY.
